UNITED STATES PATENT OFFICE.

WALTER SCOTT, OF PLAINFIELD, NEW JERSEY; ISABELLA SCOTT AND DAVID JOHN SCOTT
EXECUTORS OF SAID WALTER SCOTT, DECEASED.

LUBRICATING DEVICE.

No. 879,916.

Specification of Letters Patent.

Patented Feb. 25, 1903.

Application filed June 22, 1905. Serial No. 266,382.

To all whom it may concern:

Be it known that I, WALTER SCOTT, a citizen of the United States of America, and a resident of Plainfield, Union county, New Jersey, have invented certain new and useful Improvements in Lubricating Devices, of which the following is a specification.

The present invention relates generally to lubricating devices, and has more particularly reference to means for lubricating the reversing roll spindle of a bed and cylinder printing machine. The problem of properly lubricating this reversing roll spindle is a most important one as will be understood from the following: A machine of the character described is usually provided with a rotating impression cylinder, a reciprocating bed having an upper and a lower rack and a gear adapted to alternately engage with the two racks to impart the proper reciprocation to the bed. Suitable means as end slots on the bed and a roll moving the gear are also provided for reversing the motion of the bed at the end of the stroke in either direction. This reciprocating bed which is very heavy makes a number of reciprocations per minute; in fact, in the highly developed types the speed is considerable. Owing to the impossibility of adjusting the pressure of the air cushions which aid in retarding the motion of the bed at each end to a nicety, considerable strain is frequently placed upon this reversing roll as it practically receives all the thrust of the bed on the reversal. It will therefore readily be seen that abundant lubrication is necessary upon the spindle carrying this reversing roll. Adding to these considerations the fact that these parts are located under the machine where it is difficult to reach them by hand for the purpose of lubrication, and where there is little available space owing to the proximity of the working parts, it will at once be clear that suitable means for properly lubricating the spindle are very desirable. The object of the invention is therefore the production of suitable means for automatically lubricating this spindle in a simple and efficient manner, and to this end the invention comprises the features of construction and combinations of parts as will more fully hereinafter appear.

In the accompanying drawings the invention has been embodied in a suitable form showing also a modification; but changes

may of course be made without departing from the spirit of the invention.

In the said drawings: Figure 1 is a side elevation of a portion of a printing machine with parts broken away and in section embodying the invention. Fig. 2 is a plan view of a portion of Fig. 1. Fig. 3 is a detail view of the duct which takes the lubricant from the source of supply, on the line 3—3 of Fig. 4. Fig. 4 is a view in elevation of the duct shown in Fig. 3. Fig. 5 is a detail sectional view on the line 5—5 of Fig. 3. Fig. 6 is a plan view, similar to Fig. 2, but showing a modification. Fig. 7 is a view looking in the direction of the arrow 7 in Fig. 6.

Similar numerals of reference indicate corresponding parts in the different views.

1 indicates the reciprocating bed of the machine having an upper and a lower rack 2 and 3 and provided with suitable end slots as 4 (only one of which is seen) or other suitable means as shoes in a well known manner at the end and intermediate the two racks.

Adapted to engage alternately with the said racks is the rotatable gear 5 whose axis is fixed except for a slight up and down movement, in the present instance, to engage and disengage with the racks of the bed in a well known manner. Moving with this gear is a spindle 6 carrying a friction roll 7 adapted to engage in the slot 4 by bearing against the shoes forming the said slots or other equivalent mechanism which may be carried by the bed for co-operating with the said roll to reverse the motion of the bed. In the present instance there is shown a pivoted shoe 8 which is adapted to be moved in by means of the cam 9 after the friction roll has moved in behind it. These parts are all so well known and are only shown and referred to here in order that the difficulties of lubrication may be appreciated and in order to give a clear understanding of how my invention is applied. Inasmuch as these shoes 8 move out and in and roll 7 moves in a peculiar path, indicated by α , with relation to the reciprocating bed, it is very difficult to properly lubricate the spindle especially from that side of the gear on which the spindle and friction roll are located. It is therefore proposed to locate a source of supply of lubricant 10 on that side of the gear opposite to that on which the spindle and friction roll are located and to make the location of this source of

100
105

supply of lubricant fixed. This source of supply may take any convenient form and consists, in the present instance, of a basin 11 for receiving the oil or other lubricant 5 having a channel 12 through which extends the wick or other material 13 for properly drawing the lubricant out of the same.

Mounted upon the same shaft 14 on which the gear is carried, or mounted upon the gear 10 direct as the case may be, is an arm 15 which supports the spindle 6 having a suitable duct 17 leading from its interior to its surface. This duct is connected to the duct 18 in the arm 15 and with this duct 18 in the arm 15 is 15 connected a duct 19 which extends through the gear and terminates at its outer end in an enlarged portion 20 having a plug 21 which partially closes its outer end so as to prevent the oil from flowing out in case the machine 20 should be stopped at a point where the duct 19 will be with its open end in a downward position. This plug is provided with a flaring mouth 22 having an inwardly extending lip 23 and an outwardly projecting tongue 25 24 which comes opposite to the wick or other material and wipes the oil off the same and allows it to flow in through the mouth and lip into the enlarged portion 20 of the duct 19. From thence it is transmitted through 30 the various ducts to the surface of the spindle carrying the friction roll. The fact that the duct 19 and its auxiliary members move with the gear has the effect of forcing the oil from the tongue into the enlarged portion of 35 the said duct by reason of the centrifugal force caused by the rotation of the gear.

In Figs. 6 and 7 the construction is substantially the same with this exception; that instead of the gear 26 moving up and down, 40 it slides sidewise upon the shaft 27 into and out of engagement with the two racks 28 and 29 in a well known manner. The arm 30, however, which carries the spindle 31 for supporting the friction roll 32 is fixed on the 45 shaft carrying the gear and does not slide with it and is therefore spaced a fixed distance from the source of supply 33. In this instance the duct 34 will be made sufficiently long to extend from the source of supply to 50 the arm carrying the spindle and the gear slides over the said duct as it moves into and out of engagement between the two racks.

What is claimed is:

1. In a printing machine, the combination 55 of a gear for imparting motion to the bed, a spindle moving with said gear located on one side of the same and having a duct extending from its interior to its outside surface, a friction roll carried by said spindle, a duct 60 extending through the said gear and con-

necting with the interior of the spindle, and means for supplying lubricant to the duct, extending through the said gear.

2. In a printing machine, the combination of a gear for imparting motion to the bed, a 65 spindle for supporting a friction roll located on one side of the said gear and having a duct extending from its interior to its outside surface, an arm mounted on the same shaft as the gear and having a duct connecting with 7 the interior of the spindle, a duct extending through the said gear and connecting with the duct in the arm, and means for supplying lubricant to the duct extending through the said gear. 75

3. The combination of a rotatable gear, a spindle moving with the said gear and located on one side of the same for supporting a friction roll and provided with a duct connecting its interior with its surface, a source 80 of supply of lubricant whose position is fixed, a duct, having an enlarged portion, extending through the said gear and connecting with the interior of the spindle, a plug closing the outer end of the enlarged portion of the 85 duct to prevent the lubricant from flowing out and having a mouth provided with an inwardly projecting lip, and an outwardly projecting tongue in said mouth for receiving the lubricant from the source of supply and 90 allowing it to flow through the mouth and lip into the enlarged portion of the duct. 95

4. In a printing machine, the combination of a source of supply of lubricant located in a fixed position, a spindle, for supporting a 100 friction roll having a duct from its interior to its outer surface, a rotatable gear interposed between the spindle and source of supply and having also a sliding motion toward and away from the spindle but rotating in unison 105 with the latter, and a duct adapted to receive lubricant from the source of supply and conveying it to the interior of the spindle on which duct the said gear slides. 110

5. As a means for transferring lubricant, 105 a rotating duct having an enlarged portion, a plug closing the outer end of the enlarged portion to prevent the lubricant from flowing out and having a flaring mouth provided with an inwardly projecting lip, and an outwardly projecting tongue in said mouth for receiving the lubricant from a source of supply and allowing it to flow through the mouth and lip into the enlarged portion of the duct. 110

Signed at New York city this 16th day of June, 1905.

WALTER SCOTT.
